C. G. NELSON

RADIATOR HOOD

Filed Dec. 11, 1922

INVENTOR:

Clarence George Nelson,

BY John Elias Jones,

ATTORNEY.

UNITED STATES PATENT OFFICE.

CLARENCE GEORGE NELSON, OF CINCINNATI, OHIO, ASSIGNOR TO HIMSELF AND WILLIAM F. BARGER, OF NORWOOD, OHIO.

RADIATOR HOOD.

Application filed December 11, 1922. Serial No. 606,172.

To all whom it may concern:

Be it known that I, CLARENCE GEORGE NELSON, a citizen of the United States of America, and a resident of Cincinnati, in the county of Hamilton and State of Ohio, have invented a certain new and useful Improvement in Radiator Hoods, of which the following is a specification.

This invention relates to hoods or covers used on steam and hot-water heating-radiators in buildings to protect the adjacent walls from being smutted or soiled during the operation of heating the interiors of such buildings, and it relates, more particularly, to the type of radiator-hoods in which a top-lid, a back-shield and suitable supporting-brackets are combined for removable use on the tops of assembled radiator pipes or coils in diverting the dust and other smut or foul matter from collecting on the walls adjacent the said heat conducting and radiating pipes.

The details of structure of my special form of device herein and its peculiar means of ready attachment and detachment, as well as its very simple and economical production and operating-maintenance will be fully hereinafter described in connection with the accompanying sheet of drawings, in which latter—

Figure 1 is a perspective view of my entire device herein, showing its component top-lid detached or raised above its shield-and-bracket supporting-device and without the heating-radiator to which it is adapted for use; Fig. 2, a transverse section of the assembled device herein, showing a fragmentary portion of the radiator on which it is mounted and, also, showing a fragmentary section of the adjacent wall back of the radiator, just as the invention herein would appear in use, except that it is sectioned and broken away for better detail illustration; and Fig. 3, a fragmentary, longitudinal, sectional elevation of one end of the entire assembled device, but omitting the radiator and the said back-wall, the section being taken on a vertical line with the longitudinal fore rod that is used to connect the opposite end-brackets.

A indicates the back-wall of the room in which the radiator is installed for heating purposes, the letter B indicating any ordinary multiple, vertical pipe radiator, of which but the upper parts of one set of the

longitudinal series of pipes are shown in order to illustrate the manner of attaching or mounting my improved deflector-device for preventing smut-deposits on the said back-wall A and diverting or directing the radiated heat in the proper manner downwardly and forwardly into the room or space to be heated. C indicates the usual hollow integral connecting-member used between radiator columns or transverse series of heat-conducting pipes for assembling them in longitudinal series and spacing them apart, D being a longitudinal rod or bolt connecting all the longitudinal series of columns in assembled form, as customary.

4 indicates a horizontal top lid or cover, of rectangular form and having a drop flange or edging 5, of any suitable depth, and made just like any ordinary detachable or removable box lid but of metal, sheet or cast, as occasion or choice may demand. This lid may be of any required length suited to the radiator on which it is to be mounted for use. It is an independent lid whereby it can be conveniently handled for cleaning, painting, decorating, or any other useful or ornamental purpose, aside from the other parts of my device and the radiator herein. On the underside of the body-portion of the top-lid 4 (see Figs. 2 and 3) I preferably, but not essentially, provide a woven textile or other fabric 6 that is detachably held in place therein by means of a rectangular border wire-frame 7 whereby it can be readily handled for insertion and withdrawal in catching and holding the dust and foul collections beneath the said top-lid 4 and, also, in washing or otherwise removing the said foul collections whenever required. This inner lining 6 can, of course, be dispensed with if desired. Corresponding brackets 8 and 9 are provided, one at each end of the radiator, and duly spaced apart, as well as connected together, by means of rods 10 and 11, such rods being incased within spacer-tubes 12 whose opposite ends abut the inner faces of the said brackets and whose lower faces rest on the longitudinal series of horizontal connecting-tops 13, as best seen in Fig. 2, for due support.

The outer faces of said brackets are ribbed along their edges so as to provide countersunk main portions in which the nutted opposite ends 14 of the said rods 10 and 11 lie out of obstructing vertical line of placing.

the top-lid 4 on the said brackets for use, as best seen in Fig. 3.

Bows 15 and 16 are provided with cross-bars 17 that straddle or span and rest upon the upper faces of the said spacer-tubes 12 at a suitable distance apart, the opposite ends of said cross-bars being flared downwardly at 18 to act or serve as stops and the said bows being each used to encircle one of the hollow connecting-members C between the longitudinal series of connecting-tops 13 of the radiator-pipes, as best seen in Fig. 2, for holding the brackets in place on the radiator, nuts 19 being engaged on the upper threaded ends of the said bows for drawing the curved parts of the bows into tight engagement with said connecting-members C and said cross-bars in tight contact with the upper faces of the said spacer-tubes. Thus the entire device is properly and easily assembled, as well as tightly held in place on the radiator top, the top-lid 4 alone being independently and detachably mounted on the brackets without fastening and thus easily removed or replaced.

A horizontal flange 20 extends inwardly from each of the two supporting-brackets 8 and 9 along their top edges, and a similar vertical flange 21 extends inwardly from the side edges of the brackets, to impart the required strength to the brackets.

22 indicates a metal plate extending downwardly from the flanges 21 of the brackets 8 and 9, screw-bolts 23, 23 being used at each end to attach it in place on said flanged parts 21 so that it is properly suspended or supported in shielding-position back of the radiator to divert the heat and foreign or foul matter from the back-wall A and serve to protect the latter from smirching as well as to direct the heat forwardly into the room for the desired service and use.

The lower edge 24 of the shield or plate 22 is bowed or flexed backwardly somewhat toward the wall A so that it may contact with that wall and not allow any heat or foul, foreign matter to escape along the wall upwardly back of the radiator, an auxiliary felt pad 25 being attached along the said lower edge of the shield to still further protect the face of the wall from injury and to make a better contacting-surface than the ordinary thin edge of the metal plate might alone make in actual use.

It will be obvious that the device is easily handled to and from place, as well as kept clean, and its great simplicity assures easy production and assembling, and, also, its

very economical cost. It will also be obvious that a material advantage exists and is presented in the use of the very plain and simple form of top-lid 4, especially when it can be so readily decorated or painted to harmonize with surrounding walls or decorations in the room where the radiator is installed.

In order to remove the device from place on the radiator top the top-lid 4 is first lifted from its place; then the nuts 19 on the upwardly-extended ends of the bows or yokes 15 and 16 can be easily removed from place so as to disjoin or uncouple the back-plate and its bolt-connected supporting-brackets from attached-place on the top of the radiator, leaving said bows alone behind for quite ready gravity-disengagement from the connecting-members C and subsequent withdrawal by hand from between the heater-tubes. All these parts can then be easily cleaned ready for use again, including the fabric-lining 6 from within the top-lid 4.

It will also be seen that the rods or bolts 10 and 11 and their incasing spacer-tubes 12 may vary in length and so can the top-lid 4, as well as the back-shield 22, to suit various widths or fronts of radiators, thus leaving the brackets and the securing bows or yokes to remain unchanged or constant.

I claim:—

In a radiator-hood and protector-shield device of the character described, the combination of a pair of spaced forwardly-projecting brackets, a pair of longitudinally-parallel rods detachably-connecting the said pair of brackets, a pair of re-inforcing tubes with each one of the pair telescopically-engaging one of the said rods and spacing the said pair of brackets against collapsing end-thrusts, a pair of vertical yokes provided with detachable horizontal spanner or cross bars whose opposite ends are adapted to rest upon the said tube-inclosed rods and with the said yokes detachably-engaging hollow integral-connections between each of several adjoining pairs of the vertical radiator-pipes, a removable top-lid on the radiator adapted to collect dust or other particles of foreign matter on the bottom thereof and simultaneously divert the rising heat-current into the space to be heated, and a vertical metal shield detachably-suspended from the rear side of the said brackets and having a wall-protecting padded edge, substantially as shown and described.

CLARENCE GEORGE NELSON.
